Primary Examiner — Calvin E Vansant

Assistant Examiner — Giang Hoang Tran

(74) Attorney, Agent, or Firm — Harness, Dickey & Pierce, P.L.C.

CLAIM

The ornamental design for the bicycle pedal, as shown and described above.

DESCRIPTION

FIG. 1 is a front, top perspective view of a bicycle pedal showing a first embodiment of my new design;

FIG. 2 is a left side view thereof;

FIG. 3 is a right side view thereof;

FIG. 4 is a front side view thereof;

FIG. 5 is a rear side view thereof;

FIG. 6 is a top view thereof; and,

FIG. 7 is a bottom view thereof.

The broken lines in the figures show portions of the bicycle pedal that form no part of the claimed design.

1 Claim, 4 Drawing Sheets
